ART OF CONVERTING HIGH BOILING HYDROCARBON
OILS INTO LOWER BOILING HYDROCARBON OILS

Filed June 1, 1931

UNITED STATES PATENT OFFICE

2,009,367

ART OF CONVERTING HIGH BOILING HYDROCARBON OILS INTO LOWER BOILING HYDROCARBON OILS

Robert E. Wilson, Chicago, Ill., assignor to Standard Oil Company, Whiting, Ind., a corporation of Indiana

Application June 1, 1931, Serial No. 541,516

5 Claims. (Cl. 196—66)

The present invention relates to the conversion of relatively high boiling hydrocarbon oils into relatively low-boiling hydrocarbon oils, for example oils suitable as fuel for internal combustion engines. The present invention is particularly directed to improvements in such conversion operation conducted under superatmospheric pressure conditions.

In certain of such operations, the oil is raised to and maintained at cracking temperature and under a relatively high superatmospheric pressure for a predetermined period of time. The oil is then passed into a zone of substantially lower pressure wherein a substantial portion of the conversion products, with the exception of the heavy tar-like residues, is vaporized by the contained heat of the oil. The tarry residues are withdrawn from the system and the vapors are subjected to fractional condensation whereby the constituents heavier than those desired in the distillate product are condensed and separated from the desired low boiling products, such higher-boiling portions, if desired, being returned, along with fresh stock, to the original cracking operation.

In accordance with the present invention, the oil is brought to and maintained at cracking temperature and under a relatively high superatmospheric pressure for a predetermined period of time, as in the above type of operation, and is then subjected to successive pressure reducing stages under controlled conditions, whereby a number of advantages are secured, as more fully pointed out hereinafter.

Referring more in detail to the drawing, the numeral 5 indicates a valved line leading from any suitable source of hydrocarbon oil which is to be converted into lower boiling hydrocarbon oils. The oil is supplied through line 5 under pressure by any suitable means, for example, a pump (not shown), and is passed through a coil 6 in the upper portion of a fractionating column 7, wherein the oil is partially heated by hot vapors in the column. The oil passes from coil 6 into a line 8 provided with valved branch-pipes 9 and 10. Branch-pipe 9 leads to a coil 11 mounted in the upper portion of a flash chamber 12 and branch-pipe 10 leads to a coil 13 mounted within the upper portion of an evaporator chamber 14. Thus, all the oil being fed into the system may be passed to either of the coils 11 and 13, or closely controlled portions of it may be fed simultaneously to coils 11 and 13. The oil from coil 13 passes through line 15 into a second coil 16 mounted below coil 13 in the upper portion of evaporator chamber 14. Trap-out plates

17 and 18 are provided in the evaporator chamber 14 below coils 13 and 16, respectively. The oil after passing through coils 13 and 16, passes into a line 19 leading to a lagged stock supply or mixing drum 20 and the oil from coil 11 passes into a line 21 which is connected to the line 19. Oil fed to coil 11 in tower 12 and to coils 13 and 16 in tower 14 is thus again collected, after preheating, in line 19 and mixing drum 20.

In drum 20 the preheated fresh stock is admixed with hot oil products introduced therein through lines 19, 33a, 43 and 47, as will be herein-after described. A preheated mixed or composite feed stock is thus collected in the drum 20.

A line 22 leads from the bottom of mixing drum 20 to a hot-oil pump 23, by which the hot composite feed stock from drum 20 is forced through line 22a to a heating coil 24 suitably mounted in a combustion furnace shown diagrammatically at 25. The heated oil is brought to the desired cracking temperature in coil 24 and then passes through line 26 to a reaction chamber or soaking drum 27, the line 26 being preferably connected to one end of the chamber 27. During its passage through coil 24, the oil is heated to cracking or conversion temperature, under a high superatmospheric pressure, for example, above 450 lbs., and preferably 750 to 900 lbs., and flows at a velocity sufficient to avoid substantial deposition of coke within the coil 24. The highly heated products discharged from coil 24 into chamber 27 are maintained therein at cracking temperature and under superatmospheric pressure, approximately that at the coil outlet, for example, a temperature of 875° F. and a pressure of 750 lbs. may be maintained in the chamber 27.

The highly heated products are passed from the other end of the chamber through a line 28 to the lower portion of the evaporator chamber 14, the line 28 having a pressure reducing valve 29, the chamber 14 being maintained under a pressure lower than that maintained in the reaction chamber 27, but in general exceeding 100 lbs. gauge. For example, a pressure of from 125 to 225 lbs. may be maintained in chamber 14, a preferred range being from 150 to 200 lbs. Under these conditions, a substantial vaporization of light products takes place, but at a higher temperature (above 735° F., preferably above 750° F. and at which cracking takes place at a substantial rate) and with a lower proportion of volatilized products heavier than the desired low-boiling products than in operation as hitherto practiced, wherein the cracked products were separated at reduced pressures of, say 60 lbs. or lower. At the

- same time, the unvaporized liquid or tar, being of lighter grade, may be maintained at the higher temperature prevailing, at which cracking occurs without excessive or disturbing carbonization.
- 5 The separated vapors ascend the tower 14 and come into intimate contact with downflowing reflux, whereby any heavy entrained constituents are removed. This reflux which contains heavier constituents of the vapors is condensed therefrom by the cooling action of the fresh stock flowing through coils 13 and 16, and collects on the trap-out plates 17 and 18 from which any portion of the condensate may overflow into the lower portion of the evaporator tower. The amount of such condensate which overflows may be closely controlled by withdrawing predetermined portions of the condensate collected on the trap-out plates 17 and 18 through valved lines 33 and 34, respectively. The condensate so withdrawn from plates 17 and 18 through lines 33 and 34 is passed through line 33^a to the drum 20 where it is mixed with the other constituents of the feed stock supplied to the coil 24 in the manner already described. Ordinarily it is preferred to effect condensation of vaporous products above the plate 17 which are lower boiling than those condensed above plate 18 and below plate 17, the resulting heavier condensate on plate 18 being permitted to overflow plate 18 and the resulting lighter condensate on plate 17 comprising substantially "clean stock" which is passed to the composite stock tank 20. The heavier condensate thus permitted to overflow plate 18 functions to remove entrainment from the vapors in the portion of tower 14 below plate 18. The portion of the tower 14 below the trap-out plate 18 may be provided with a plurality of elements (not shown) for effecting intimate contact of the vapors and liquid therein and removing entrained matter from the vapors, such as baffle plates, screen plates, ring and disk plates, or the like. The latter plates have the advantage of less tendency to coke up.
- 45 The remaining vapors are passed from the upper end of tower 14, through a valved line 32, to the lower portion of the fractionating column 7 wherein they are fractionated, to separate the constituents heavier than those desired in the low-boiling product or gasoline.
- 50 The separated unvaporized liquid or tar is removed from the bottom of evaporator tower 14 through line 30 provided with a suitable pressure reducing valve 30^a, and passes through one of the valved branch lines 31 into the low-pressure flash chamber, or tower, 12. A low superatmospheric or approximately atmospheric pressure is maintained within the tower 12, whereby substantially all but the heavy residual constituents of the liquid or tar, passed thereto from tower 14 is flashed into vapors by the contained heat of such products, the flashed vapors constituting desirable charging stock for a cracking operation wherein low-boiling oils, such as gasoline, are produced. For example, the tower 12 may be maintained under atmospheric pressure, or slightly thereabove, say from 1 to 30 lbs. gauge. The interior of the tower 12 may be provided with a plurality of baffle elements 35 for effecting intimate contact between ascending vapors and descending liquid therein, which may be similar to those provided within the tower 14. The heavy residue is withdrawn from the bottom of tower 12, and from the system, through a valved line 37. The flashed vapors ascend the tower 12 and come into intimate contact with cooler down-
- flowing liquid whereby any entrained tarry residues may be removed therefrom. This cooler liquid may comprise certain heavy fractions condensed from the vapors by the cooling action of the coil 11 through which is passed the relatively cool fresh stock, as already described.
- 5 The vapors pass out of the upper end of tower 12, through a valved line 38 to a condenser 39, wherein they are condensed. The condensate, together with any uncondensed vapors or gases, passes from condenser 39 through a line 40 to a separator drum 41 wherein the liquid condensate and vapors or gases separate, the latter being discharged through a valved line 42. The condensate is drawn from separator 41, through a valved line 43, by pump 43^a and forced to the mixing drum 20 and/or through pipe line 43^b into the upper portion of tower 14 at a point above plate 17. Thus, any portion of the condensate from separator 41 may be permitted to overflow the plate 17 to function as a reflux medium for the portion of column 14 therebelow. The fractionated vapors, supplied to column 7 from tower 14, pass out of the top of column 7 through a valved line 49 to a condenser 50, wherein they are condensed. The condensate formed in condenser 50, together with any remaining vapors or gases, passes from condenser 50 through line 51 to a separator 52. The condensate, which is the desired pressure distillate product, is withdrawn from separator 52, and from the system, through a valved line 53 which may lead to a suitable stabilizing operation or to a gas release tower connected to an absorption plant, before going to storage. The gas which at this pressure is practically free of any constituents desired in the distillate product, is withdrawn from separator 52 through a line 54 connected to valved lines 55 and 56. The line 55 leads from the system and the branch-line leads to the lower portion of the second flash tower 12, whereby all or any portion of the gases may be introduced into the body of liquid residue products therein to aid in stripping therefrom the lower-boiling constituents.
- 45 The condensate formed in the column 7 is withdrawn from the bottom of the column 7 through line 47 by pump 48 and forced to the mixing drum 20. Low-boiling hydrocarbons, desired in the gasoline distillate, are stripped from the condensate within column 7 by means of steam admitted through 47^a or by other means. The necessary cooling in the upper portion of column 7 may be effected in whole, or in part, by the passage of fresh feed stock through coil 6. If desired, additional cooling may be effected by passing a cooling medium through coil 44.
- 50 Any vapors given off within the mixing drum 20 may be withdrawn therefrom and passed through valved vent line 57 into tower 14, preferably the upper portion thereof.
- 55 Steam, or other inert gas, may be introduced into the liquid in the lower portion of flash chamber 12 instead of the gases from separator 52. However, since these gases are under a relatively high pressure it has been found that they are capable of effecting the desired stripping of the heavy tar residues in the bottom of chamber 12 and hence it is preferred to so employ them.
- 60 In a specific operation, gas oil having a gravity of 29.4 Bé. was charged into the system through line 5.
- 65 In the operation of the process, for example, with a gas oil cracking stock and with a temperature in the reaction chamber 21 of approximately 875° F. and a pressure of about 750 lbs.,

the unvaporized liquid or tar in the evaporator 14 may be maintained at a temperature of 750 to 825° F. and under a pressure of 125 to 150 lbs., the liquid in tower 14 having a gravity of 10 to 12°

5 A. P. I. Under these conditions, of pressure and temperature, additional cracking is effected in the body of tar in tower 14 at a substantial rate, but without disadvantageous coke formation. With similar stock and heating conditions, but 10 with lower pressures, below 75 lbs. for example, in the evaporator tower 14, a much heavier tar forms therein under very considerably lower temperatures, say 700 to 715° F., under which conditions no substantial cracking occurs, or if the 15 temperature of the tar body were raised, serious and disadvantageous coking would occur.

Under the conditions above set forth for operation in accordance with the present invention, the vapors are released in the evaporator tower 14 at 20 substantially higher temperature, 750 to 825° F., or higher, and are hence available to secure a higher temperature of preheating in the feed stock passed through the coils 13 and 16, and also in the reflux condensates withdrawn through the 25 lines 33 and 34, and, as a result, the composite feed stock in the feed tank 20 is maintained at substantially higher temperatures, say 35 to 50° F. higher than with lower pressure prevailing in the evaporator tower 14, as in prior practice. 30 Furthermore, the additional cracking taking place in the tarry body in the evaporator 14 results in the formation of additional vaporizable constituents, which are released when the tar is discharged into the flash tower 12, and these additional light constituents are made available for 35 cracking or condensation in the condenser 39 and return to the composite feed tank 20. Although these advantages are secured, at the same time, the conditions prevailing in the evaporator tower 40 7 are such that the reflux condensate condensed therein and returned to the composite feed tank 20 is likewise at a somewhat higher temperature than has been the case in prior practice.

The operation of the evaporator 14 and the 45 fractionating column 7 may be so controlled as to secure a condensation of constituents heavier than the desired products in the upper portion of the tower 14, and a condensation and stabilization of the desired products in the fractionating column 7.

It will be apparent that the details of the apparatus and process as set forth hereinbefore may be materially modified within the scope of the invention, and are not intended to be regarded as 55 limitations upon the scope of the invention, except as set forth in the accompanying claims.

I claim:

1. The method of converting higher boiling hydrocarbon oils into lower boiling hydrocarbon 60 oils which comprises heating such oil to a temperature of at least 850° F. while maintaining it under a superatmospheric pressure of at least 750 lbs. per square inch, passing the highly heated oil to a zone of substantially lower superatmospheric pressure of at least 100 lbs. per square inch wherein the desired low-boiling products together with a portion of the products heavier than the desired products are vaporized by the 65 contained heat of the oil and the unvaporized products are maintained at a temperature of at least 750° F., separately withdrawing the vaporous and unvaporized products, passing the unvaporized products from said low pressure zone to another zone of still lower pressure wherein substantially all of the remaining 70 heavier constituents thereof are vaporized by the contained heat of the oil and the unvaporized products are maintained at a temperature of at least 750° F., separately withdrawing the vaporous and unvaporized products, passing the unvaporized products from said second-named low pressure zone before the latter product is withdrawn therefrom.

ents thereof desirable as cracking stock are vaporized by the contained heat of the said products, separately withdrawing the vaporous and unvaporized portions, subjecting the vapors from said first-named low pressure zone to a fractionating operation wherein the heavier constituents thereof are condensed as reflux condensate, passing said reflux condensate to the oil undergoing cracking, subjecting the fractionated vapors to a condensing operation, and passing 10 the uncondensed constituents thereof through the unvaporized product in said second-named low pressure zone before the latter is withdrawn therefrom.

2. The method of converting higher boiling 15 hydrocarbon oils into lower boiling hydrocarbon oils which comprises heating such oil to a temperature of at least 850° F. while maintaining it under a superatmospheric pressure of at least 450 lbs. per square inch, passing the highly heated 20 oil to a zone of substantially lower superatmospheric pressure of at least 100 lbs. per square inch wherein the desired low-boiling products together with a portion of the products heavier than the desired products are vaporized by the 25 contained heat of the oil and the unvaporized products are maintained at a temperature of at least 750° F., separately withdrawing the vaporous and unvaporized products, passing the unvaporized heavier products from said low pressure 30 zone to another zone of still lower pressure wherein substantially all of the remaining heavier constituents thereof desirable as cracking stock are vaporized by the contained heat of the said products, separately withdrawing the vaporous and unvaporized portions, subjecting the vaporous products from said second-named low pressure zone to a condensing operation, passing the resulting condensate to the oil undergoing cracking, and passing a portion of the 35 vapors from said first-named low pressure zone through the unvaporized product in said second-named low pressure zone before the latter product is withdrawn therefrom.

3. The method of converting higher boiling 45 hydrocarbon oils into lower boiling hydrocarbon oils which comprises heating such oil to a temperature of at least 750° F. while maintaining it under a high superatmospheric pressure, passing the highly heated oil to a zone of substantially lower superatmospheric pressure of at least 100 lbs. per square inch wherein the desired low-boiling products together with a portion of the products heavier than the desired products are 50 vaporized by the contained heat of the oil and the unvaporized products are maintained at a temperature of at least 750° F., separately withdrawing the vaporous and unvaporized products from said low pressure zone to another zone of still lower pressure wherein substantially all of the remaining heavier constituents thereof desirable as cracking stock are vaporized by the contained heat of the said products, separately withdrawing the vaporous and unvaporized portions, subjecting the vaporous products from said second-named low pressure zone to a condensing operation, passing the resulting condensate to the oil undergoing cracking, subjecting the vapors from said 55 first-named low pressure zone to a condensing operation, and passing the uncondensed constituents thereof through the unvaporized product in said second-named low pressure zone before the latter product is withdrawn therefrom.

4. The method of converting higher boiling hydrocarbon oils into lower boiling hydrocarbon oils which comprises heating such oil to a temperature at least 850° F. while maintaining it under a superatmospheric pressure of at least 750 pounds per square inch, passing the highly heated oil to a zone of substantially lower superatmospheric pressure of at least 100 lbs. per square inch wherein the desired low-boiling products together with a portion of the products heavier than the desired products are vaporized by the contained heat of the oil and the unvaporized products are maintained at a temperature of at least 750° F., separately withdrawing the vaporous and unvaporized products, passing the unvaporized products from said low pressure zone to another zone of still lower pressure wherein substantially all of the remaining heavier constituents thereof desirable as cracking stock are vaporized by the contained heat of the said products, separately withdrawing the vaporous and unvaporized portions, subjecting the vaporous products from said second-named low pressure zone to a condensing operation, passing the resulting condensate to the oil undergoing cracking, subjecting the vapors from said first-named low pressure zone to a fractionating operation wherein the heavier constituents thereof are condensed as reflux condensate, passing said reflux condensate to the oil undergoing cracking, subjecting the fractionated vapors to a condensing operation, and passing the uncondensed constituents thereof through the unvaporized product in said second-named low pressure zone before the latter is withdrawn therefrom.
5. The method of converting higher boiling hydrocarbon oils into lower boiling hydrocarbon oils which comprises heating such oil to a temperature of about 900° F. while maintaining it under a superatmospheric pressure of about 750 lbs. per square inch, passing the highly heated oil to a zone of substantially lower superatmospheric pressure of at least 100 lbs. per square inch wherein the desired low-boiling products together with a portion of the products heavier than the desired products are vaporized by the contained heat of the oil and the unvaporized products are maintained at not less than 750° F., separately withdrawing the vaporous and unvaporized products, passing the unvaporized products from said low pressure zone to another zone of still lower pressure wherein substantially all of the remaining heavier constituents thereof desirable as cracking stock are vaporized by the contained heat of the said products, separately withdrawing the vaporous and unvaporized portions, subjecting the vaporous products from said second-named low pressure zone to a condensing operation, passing the resulting condensate to the oil undergoing cracking, subjecting the vapors from said first-named low pressure zone to a fractionating operation wherein the heavier constituents thereof are condensed as reflux condensate, passing said reflux condensate to the oil undergoing cracking, subjecting the fractionated vapors to a condensing operation, and passing the uncondensed constituents thereof through the unvaporized product in said second-named low pressure zone before the latter is withdrawn therefrom.

ROBERT E. WILSON.
